UNITED STATES PATENT OFFICE.

SAMUEL WHITEHALL, OF SOUTH BEND, INDIANA.

BOX-FASTENER.

935,872

Specification of Letters Patent.

Patented Oct. 5, 1909.

Application filed March 5, 1909. Serial No. 481,444.

To all whom it may concern:

Be it known that I, SAMUEL WHITEHALL, a citizen of the United States, residing at South Bend, in the county of St. Joseph and State of Indiana, have invented certain new and useful Improvements in Box-Fasteners, of which the following is a specification.

This invention relates to box fasteners. 10 One object of the invention is to provide means for securely locking the lid to the box and also effectually reinforcing the box to prevent bulging of the sides.

Another object of the invention is to provide a simple means for locking the lid on the box and also effectually preventing bulging of the sides thereto with the use of a comparatively small amount of wire as compared with the wire usually employed for 20 binding veneer boxes together.

With the above and other objects in view, the present invention consists in the combination and arrangement of parts herein-after more fully described, illustrated in the 25 accompanying drawings and particularly pointed out in the appended claims, it being understood that changes may be made in the form, proportion, size and minor details without departing from the spirit or sacrificing any of the advantages of the invention.

In the drawings:—Figure 1 is a perspective view of a box illustrating the fastening means in operative position at one end of the box and in the process of application at 35 the opposite end of the box. Fig. 2 is a vertical sectional view through a portion of one end of the box. Fig. 3 is a detail view of one of the fastening means.

Referring now more particularly to the 40 accompanying drawings, the reference character 1 indicates the bottom of the box, 2 the sides, 3 the ends and 4 the top or lid of the box, the bottom, sides and top, each having a cleat 5 at each end against the inner face of which are disposed the ends 3.

Ordinarily veneer boxes are bound together by wire which requires considerable wire for the purpose. I aim to obviate the usual amount of wire employed for binding 50 boxes and yet efficiently secure the parts together and lock the top or lid against displacement. To this end I provide a U-shaped member 6 composed of wire and provided at the bottom and top at each end with alining 55 pairs of perforations 7, which perforations

coincide with the perforations 8 in the upper and lower cleats 5. Through these perforations I pass the legs 9 of the U-shaped fastenings 6 and when the bight portions 10 of the U-shaped fastenings are disposed against the outer face of the bottom 1, I bend the outer ends of the legs 9 over the outer face of the lid of the box and then downwardly against the outer faces of the corresponding upper cleats, as indicated at 11, with the extremities of each leg directed underneath of the upper cleats 5. I then drive staples into the under face of the upper cleat 5 in embracing relation with said extremities of the legs 9 to effectually hold the extremities against accidental displacement.

Thus it will be seen that my improved fastening means serves not only as a means for locking the top or lid in position, but it will also be seen that it reinforces the box 75 in order to prevent the contents thereof from bulging out the top and bottom sides such being the widest and weakest part of the box.

The fastening is just as effective for small size boxes as a reinforcing wire passed entirely around the box and effects a considerable saving of wire. Furthermore, in the use of my improved fastening means there are no sharp points extending from the box to injure persons handling the same.

What is claimed is:—

1. In a box fastening, a box provided at each end with pairs of perforations, and U-shaped fastening members each having legs passed through the corresponding pairs 90 of perforations with their bight portions disposed beneath the bottom of the box and the extremities of the legs thereof bent over the top and ends of the box.

2. In a device of the character described, 95 a box, including a bottom, top, sides and ends, cleats secured to the opposite ends of the bottom, top and sides, the bottom and top, and the cleats secured thereto being provided with alining perforations, and U- 100 shaped members having legs passed through the alining perforations at each end of the box with the bight portions of the members disposed against the under face of the bottom and with the ends of the legs bent over 105 the upper face of the top downwardly against the outer faces of the cleats secured to the top with their extremities directed inwardly against the under face of the cleats of the top, and staples driven into the under 110

face of the cleats of the top in embracing relation with said extremities of the legs of said fastening members.

3. The combination with a box including 5 a top, U-shaped members having their legs passed through the bottom and the top of the box at each end of the latter with the bight portion of each U-shaped member disposed against the bottom of the box and the extremities of the legs bent over the top and 10 directed inwardly of the box.

4. The combination with a box including 15 a top, U-shaped members having their legs passed through the bottom and the top of the box at each end of the latter, with the

bight portion of each U-shaped member disposed against the bottom of the box and the extremities of the legs bent over the top and directed inwardly of the box, and staples driven into the box in embracing relation 20 with the inwardly directed portions of the extremities of said legs to prevent displacement of the extremities of the legs.

In testimony whereof I affix my signature, in presence of two witnesses.

SAMUEL WHITEHALL.
